Primary Examiner — Anhdao Doan*Assistant Examiner* — Mary Shannon Malley(74) *Attorney, Agent, or Firm* — Fish & Richardson P.C.(57) **CLAIM**

The ornamental design for a surgical system base, as shown and described.

DESCRIPTION

FIG. 1 is a perspective view of my surgical system base.

FIG. 2 is a front view of my surgical system base.

FIG. 3 is a back view of my surgical system base.

FIG. 4 is a left side view of my surgical system base.

FIG. 5 is a right side view of my surgical system base; and, FIG. 6 is a top view of my surgical system base.

The broken lines in each figure illustrate environmental features that form no part of the claimed design.

1 Claim, 5 Drawing Sheets(56)
